UNITED STATES PATENT OFFICE.

FREDERICK A. PRESTON, OF HIGHLAND PARK, ILLINOIS, ASSIGNOR TO THE P & M COMPANY, OF CHICAGO, ILLINOIS, A CORPORATION OF ILLINOIS.

RAIL ANCHOR.

Application filed May 6, 1926. Serial No. 107,063.

This invention relates to improvements in rail anchors and has for its objects the provision of a new and improved two-piece anchor device which, when applied to a rail, 5 will exert a firm grip on opposite edges of the rail base, and in which the parts of the device will be maintained in frictional engagement with each other by the resilience of one of the members. 10 A more specific object of the invention is to provide an improved two-piece anchor device consisting of a spring yoke member adapted to extend across beneath the rail base, and a tapered key member adapted to 15 be driven between the rail base and one end of the spring yoke so as to stress the yoke. In this connection the invention contemplates an arrangement of parts in which the tapered key is driven through the yoke in a 20 direction toward the adjacent cross tie so that the side face of the yoke will bear flatwise against the tie.

The yoke is of such form as to provide a tie engaging face which extends a substantial 25 distance below the bottom surface of the rail base so that the anchor device may be used in connection with pole ties without danger of the yoke member being forced into the space between the rail base and the 30 curved upper corners of such ties.

The invention also includes a new and improved form of wedge key in which the wedging surfaces are so formed as to stress one end of the yoke both vertically and 35 laterally of the rail and so as to exert a torsional stress on the body of the yoke when the key is driven home.

The invention further contemplates the other new and improved constructions and 40 arrangements of parts, as will be hereinafter described in connection with the preferred embodiment of the invention shown in the accompanying drawing.

In the drawing:

45 Fig. 1 shows a cross section of the base portion of a railroad rail, with a rail anchor constructed in accordance with my invention applied thereto.

50 Fig. 2 is a plan view showing the device in position on the rail so as to abut against one of the vertical faces of a cross tie.

55 Fig. 3 is a side view in elevation of the structure shown in Figs. 1 and 2.

Fig. 4 is a view similar to Fig. 1 showing the yoke in position on the rail base and

illustrating in dotted lines the manner in which the yoke is applied.

Fig. 5 is a view in perspective of the yoke member, and

Fig. 6 is a sectional view taken on line 60 6—6 of Fig. 1 so as to show the torsion of the yoke member.

The preferred embodiment of the invention consists of a yoke member 10 and a key 11, the latter of which is driven between the base portion 12 of the rail and one extremity of the yoke. 65 The yoke member embraces the opposite edges of the base of the rail and is positioned on the rail so as to bear flatwise against the vertical face of 70 a cross tie 13. The key member is driven in a direction toward the cross tie, against which the yoke bears, and is formed, as will be hereinafter described so as to stress one 75 end of the body portion of the yoke when the key is driven home.

The yoke is made preferably from a steel bar, one end of which is formed with a hook shaped portion 14 providing a short jaw 15 which fits over one edge of the rail base. 80 The space underlying this jaw is of such size that when the anchor is in its applied position, the flange 16 of the rail base is gripped tightly between the under surface of the jaw 15 and the top surface of the 85 body portion of the yoke. The portion of the body of the yoke designated by the reference character 17 is straight and bears flatwise against the undersurface of the rail base to substantially the center of the rail. 90

The tight engagement of the jaw portion 14 on the base flange of the rail normally holds the portion 17 of the yoke against the bottom surface of the rail independently of the action of the key 11. The other end of the 95 yoke is formed with a relatively large hook shaped portion 18 which extends around the flange 19 of the rail base. This hook portion of the yoke extends downwardly with respect to the bottom of the rail from a 100 point near the center of the base, the extremity being bent upwardly and inwardly with respect to the rail so as to project over the inclined surface of the rail base. The hook portion is of such size that it may be hooked over the edge of the rail base a sufficient 105 distance to permit the short jaw 15 to clear the opposite edge of the rail base. This manner of applying the yoke to the rail is indicated in dotted lines in Fig. 4. The 110

relatively large hook shaped portion, in addition to facilitating the application of the yoke to a rail extends downwardly from the rail so as to engage the tie at a substantial distance below the rail base.

After the short jaw 15 is hooked over the rail base, it may be driven into tight gripping engagement with the rail base by driving the yoke toward the right of Fig. 4. When the yoke is in its applied position, there is normally a slight clearance between the vertical surface 20 of the rail base and the vertical wall 21 of the jaw portion 14. The amount of such clearance will, of course, depend upon the thickness of the base flange of the rail and the force used in applying the yoke. If the yoke is applied to a rail having a relatively thin base flange, or if sufficient force is exerted in driving it to its applied position, the vertical wall 21 of the jaw portion may be driven into contact with the vertical surface 20 of the rail base. The yoke is held against transverse movement in a direction to loosen the grip of jaw 15 by means of the key 11. The key is angular in cross section and bears against the top and vertical surfaces of the rail base. The portion 22 engaging the vertical surface of the rail base preferably stops short of the lower edge of the rail so that the key, when it is driven to its applied position, will clear the top face of the cross tie. The top and side surfaces 23 and 24 of the key are tapered so as to provide wedge surfaces, which, when the key is driven through the yoke, longitudinally of the rail, flexes the hook portion 18 of the yoke upwardly and outwardly with respect to the rail base. The amount of flexing to which the yoke is subjected will readily appear from a comparison of the dotted line position of Fig. 1 with reference to the full line position. In addition to the vertical distortion of the yoke, the tapered surface 23 of the key twists the yoke so that the under surface of the long jaw 25 bears flatwise against the key. This torsioning of the yoke increases its grip on the rail by forcing the edge 26 of the body and the edge 27 of jaw 15 into tight gripping engagement with the top and bottom surfaces of the rail base. The tendency which the spring yoke has to return to the position from which it was sprung holds the key in tight frictional engagement with the top and vertical surfaces of the rail base and also holds the key from backing out of its applied position. The yoke may be applied to the rail on either side of the tie so that the key may be driven toward or away from the tie as desired. It is preferable, however, to drive the key toward the adjacent cross tie. With such arrangement the yoke is held by the tie at substantially right angles to the rail while the key is being driven to its applied position. In order to provide a relatively wide

striking face on the key, one end of the key is provided with a lateral flange 28.

The anchor device is shown in the drawings in connection with a pole tie for the purpose of illustrating the manner in which the relatively large hook shaped portion 18 provides a tie bearing face which extends below the curved upper corner of the tie. When the anchor is applied adjacent to a cross tie having squared upper corners, the body portion of the yoke bears throughout its entire length against the cross tie.

When the anchor is in its applied position, the upward distortion and the torsional stress of the yoke produced by the tapered surface 23 of the key, forces the body portion of the yoke up against the bottom surface of the rail base and holds the key in firm frictional contact with the top surface of the base. The outward flexing of the hook 18, produced by the tapered side portion 24 of the key, exerts a spring grip transversely of the rail, which holds the jaw portion 14 in tight gripping engagement with the opposite edge of the rail base and holds the key 11 in frictional engagement with the vertical surface 29 of the rail base.

While the invention has been shown and described in connection with one specific embodiment, it will be obvious that modifications in structure and arrangement of the parts may be made without departure from the spirit of the invention. The invention therefore contemplates all such modifications in structure and arrangement of parts as come within the scope of the appended claims.

I claim:

1. A rail anchor comprising a rail base embracing yoke and a key adapted to be driven into wedging position between the base flange and the yoke; the engagement between the key and yoke being such that the yoke is subjected to torsional stress when the key is driven to its wedging position.
2. A rail anchor comprising a rail base embracing yoke and a key adapted to be driven into wedging position between the base flange and the yoke; the key being formed with a tapered surface, whereby one end of the yoke is flexed upwardly and outwardly when the key is driven to its applied position.
3. A rail anchor comprising a rail base embracing yoke and a key adapted to be driven into wedging position between the base flange and the yoke; the key being formed on its top and side faces with tapered surfaces, whereby one end of the yoke is flexed upwardly and outwardly and the body portion of the yoke is subjected to torsional stress when the key is driven to its applied position.
4. A rail anchor comprising a spring metal yoke formed at one end with a jaw

portion adapted to grip one edge of the rail base and at the other end with a relatively large hook shaped portion which extends downwardly from the bottom surface of the base and over the upper surface thereof, and a key member formed with tapered surfaces and adapted to be driven longitudinally of the rail into wedging position between the top and vertical faces of the rail base and the inner face of said hook shaped portion of the yoke.

5. A rail anchor comprising a spring metal yoke member adapted to bear against a cross tie and formed at one end with a jaw portion adapted to grip one edge of the rail base and at the other end with a relatively large hook shaped portion which extends downwardly from the bottom surface of the base to provide an extended tie bearing face and projects over the upper surface of the base, and a key member formed with tapered surfaces and adapted to be driven toward the tie against which said yoke abuts and into wedging position between the top and vertical faces of rail base and the inner face of said hook shaped portion of the yoke.

6. A rail anchor consisting of a resilient yoke adapted to bear against the cross tie and formed at one end with a hook shaped portion, providing a rail base receiving recess, the vertical dimension of which is normally less than the thickness of the rail base when the anchor is free of the rail and adapted to be driven into wedging engagement with one edge of the rail base, formed at the other end with a relatively large hook portion which extends downwardly from the bottom of the base to provide an extended tie abutting face and terminates in the position above the top surface of the rail base, and a key adapted to be driven in a direction toward the cross tie against which the yoke bears and into wedging position between

the rail base and the inner surface of said large hook portion; said key being formed 45 to confine its engagement with the rail to the top and vertical faces of the rail base, and being formed on its top and side faces with tapered surfaces which flex the large hook portions of the yoke upwardly and outwardly with respect to the rail base and subject the body portion of said yoke to torsional stress when the key is driven to its operative position.

7. A rail anchor consisting of a rail base 55 embracing yoke adapted to be applied to the base portion of a rail in a position to bear against a cross tie and formed at one end with a jaw, the under surface of which is normally parallel to the edge of the rail 60 base in a direction longitudinally of the rail, and a key formed on its top with a surface tapered longitudinally of the rail and adapted to be driven between the rail base and said parallel surface of said jaw, whereby 65 by the jaw end of said anchor is flexed to move said under surface into flat gripping engagement with the tapered surface of said key.

8. A rail anchor consisting of a rail base 70 embracing yoke adapted to be applied to the base portion of a rail in a position to bear against a cross tie and formed at one end with a jaw portion, the under surface of which is normally parallel to the edge of the 75 rail when the anchor is in its initial position on the rail, and a key formed on the top and side faces with tapered surfaces and adapted to be driven between the rail base and said under surface of said jaw portion, 80 whereby the jaw portion is flexed to bring the above mentioned parallel surfaces into flat gripping engagement with the tapered surfaces of said key.
